ICE RETAINER FOR A DRINKING GLASS

Edward H. Seeley, Binghamton, N.Y., assignor to
Clarence S. Oakley, Jr., Binghamton, N.Y.

Filed Jan. 28, 1963, Ser. No. 73,328

Term of patent 7 years

(Cl. D44—29)

FIG.1

FIG.2

FIG.4

FIG.3

FIGURE 1 is a perspective view of an ice retainer for a drinking glass showing my new design;

FIGURE 2 is a top plan view thereof;

FIGURE 3 is a bottom plan view; and

FIGURE 4 is a front elevational view.

The essential features of my design are shown in full lines on the drawing.

The characteristic feature of my design resides in the combination in a split-ring ice retainer having a rectangular cross-sectional shape in the annular portion of three arcuately symmetrical spaced lobes extending inwardly from and having a common lower plane with the said

annular portion, the said spacing between the lobes adjacent the free ends of the split-ring and the remaining lobe being substantially one-half the transverse dimension of the said lobes, all as shown.

I claim:

The ornamental design for an ice retainer for a drinking glass, substantially as shown and described.
